TRANSMISSION SYSTEM

Doren Mitchell, Bound Brook, and Harry Nyquist,
Millburn, N. J., assignors to American Telephone and Telegraph Company, a corporation of New York

Application October 11, 1938, Serial No. 234,434

14 Claims. (Cl. 179—1.5)

This invention relates to a transmission system and particularly to a method of and means for assuring secrecy in the transmission of messages.

5 An object of the invention is the transmission of messages in such a manner that intelligible reception of the messages by unauthorized persons will be rendered very difficult.

Another object of the invention is to obtain the 10 maximum efficiency in the use of communication circuits by decreasing the amount of "idle time" of such circuits.

In accordance with a specific embodiment of 15 the invention, a plurality of one-way speech channels are associated with a larger number of subscribers' telephone circuits; for example, six channels may be associated with ten different subscribers' circuits. Switching means are provided whereby an idle channel is selected for 20 transmission of each different speech portion of vocal interval duration occurring in the various subscribers' circuits. Properly controlled apparatus is provided at the receiving end of the line for reassembling the speech fragments or, 25 in other words, for putting the various messages back together again, this apparatus being controlled by distinctive tones transmitted over a separate control channel.

Privacy is achieved by use of an arrangement 30 of the type comprehended by the invention in view of the fact that snatches of several different conversations appear in a random manner on any one of the various speech channels. Further, the arrangement is effective as a "channel saver," a fact apparent from the opening sentence 35 of a preceding paragraph wherein it is pointed out that the number of subscribers' telephone circuits served by the speech channels is greater than the number of said channels. This makes 40 it possible to take advantage of the now well-known fact that, during a so-called conversation period on a four-wire circuit, one side of the circuit is actually in use only about one-third of the time.

45 A feature of the invention is switching means effective when a speech fragment of vocal interval duration is applied to a speech channel, to preselect the "next" idle channel, that is, the channel to which the speech fragment of vocal 50 interval duration occurring next will be applied.

Another feature of the invention is the use of tones to control the apparatus provided for reassembling the various speech fragments of vocal interval duration at the receiving end of the line.

55 In general the term "vocal interval" as used

above means the duration of a succession of syllables no one of which is separated from the preceding syllable by an interval as great as the "hang-over time" of the system, weak beginnings and endings, i. e., portions not capable of causing relay operation, being considered parts of the silent interval. "Hang-over time" is a term commonly used in connection with systems including voice-operated devices and means the period that a voice-operated device remains, due 5 to its own characteristics, in operated position after the operating impulse has been removed. Hang-over time insures that weak endings of 10 syllables, not capable by themselves of holding the relays in operated position, be not lost by 15 clipping and may be increased or decreased as the type of system demands.

Applicants feel assured that the arrangement 20 of the present invention is capable of functioning with a high degree of privacy with a hang-over time of about 150 milliseconds; it will be understood, however, that this period is subject to variation depending upon conditions encountered in different systems.

It will be understood, of course, that the duration 25 of the vocal intervals themselves will vary in accordance with the characteristics of the system and the nature of the communication.

A full understanding of the operation of the arrangement contemplated by the invention as 30 well as appreciation of the various advantageous features thereof may be gained from consideration of the following detailed description in connection with the accompanying drawings in 35 which:

Figure 1 shows diagrammatically a two-way telephone system embodying features of the invention;

Fig. 2 shows in detail the switching arrangement 40 of one terminal of the system of Fig. 1.

Referring now to the drawings, there are represented in Fig. 1, two terminals, west and east, of a two-way telephone system which may be, for example, a two-way radio telephone system. Five subscribers' sets 12, 13, 14, 15 and 16 are shown at the west station, each of which is provided with a suitable two-way subscriber's telephone circuit; similarly, five subscribers' sets 17, 22, 23, 24 and 25, are shown at the east station, each 50 of these sets likewise being provided with a suitable two-way subscriber's telephone circuit.

The west and east terminals are connected by three west-east speech channels 26, 27 and 42, one west-east control channel 43, three east-west 55

speech channels 44, 45 and 46 and one east-west control channel 47.

The west terminal switching apparatus is represented by box 52 and the east terminal switching apparatus by box 53; these switching arrangements will be described in detail subsequently by reference to Fig. 2.

The telephone circuit of subscriber's set 12 has associated with it three oscillators 54, 55 and 56, each of which sends out a distinctive tone of frequency f_1 , f_2 and f_3 , respectively; similarly the telephone circuit of subscriber's set 13 has associated therewith oscillators 57, 58 and 59, the telephone circuit of subscriber's set 14 has associated therewith oscillators 64, 65 and 66, the telephone circuit of set 15 has associated therewith oscillators 71, 72 and 73, the telephone circuit of set 16 has associated therewith oscillators 84, 85 and 86. In a similar manner at the east terminal oscillators 87, 102 and 103 are associated with the circuit of set 17, oscillators 104, 105 and 106 with the circuit of set 22, oscillators 107, 112 and 113 with the circuit of set 23, oscillators 114, 115 and 116 with the circuit of set 24 and oscillators 117, 122 and 123 with the circuit of set 25.

Each of the oscillators provided at the west terminal sends out a distinctive tone; each oscillator provided at the east terminal sends out a tone the same as that of the corresponding oscillator at the west terminal, that is, the tone sent out by oscillator 87 is the same as that sent out by oscillator 54, the tone sent out by oscillator 102 is the same as that sent out by oscillator 55 and so on. Each control channel 42 and 47 is capable of transmitting a frequency band sufficiently broad to include the fifteen distinctive tones f_1 to f_{15} inclusive. At such time as a speech fragment of vocal interval duration originating in one of the subscriber's telephone circuits is applied to one of the speech channels, a tone from one of the three oscillators associated with that telephone circuit is applied to the control channel associated with the group of speech channels, the particular tone applied depending upon which speech channel has been selected for transmission of the speech fragment.

The operation of the terminal switching arrangements will be described in detail subsequently with reference to Fig. 2; their operation will be only very briefly described at this point. Let us assume that a conversation is taking place between subscribers B (set 13) and B' (set 22) and that a speech fragment of vocal interval duration originating at set 13 has just been applied to speech channel 26. The switching arrangement 52 operates at this time to do several things, among them being to select an idle west-east speech channel (let us say channel 27) to which the next speech fragment of vocal interval duration originated by set 13, or by any of the other west sets, will be applied and to apply tone from oscillator 57 to control channel 43, the tone f_4 produced by oscillator 57 being the distinctive tone identified with channel 26 so far as subscribers' sets 13 and 22 are concerned. This tone actuates proper control apparatus of terminal arrangement 53 in order to cause the speech fragment of vocal interval duration which it accompanied to be applied to the receiving side of the telephone circuit of subscriber's set 22.

The next speech fragment of vocal interval duration originating at the west terminal will be applied to speech channel 27, this channel hav-

ing been preselected as described in the above paragraph. We will assume that this speech fragment originates at subscriber's set 14, it being assumed that subscriber C is conversing with subscriber C'. At such time as this speech fragment is applied to the channel, switching apparatus 52 acts to preselect an idle speech channel for the next speech fragment of vocal interval duration and to apply tone from oscillator 15 to control channel 43, the tone, f_8 , produced by oscillator 75 being the distinctive tone identified with channel 27 so far as subscribers' sets 14 and 23 are concerned. This tone causes operation of certain apparatus associated with east terminal switching arrangement 53 effective to apply the speech fragment of vocal interval duration coming in over speech channel 27 to the receive side of the telephone circuit of subscriber's set 23.

Speech fragments of vocal interval duration, as they originate in any of the telephone circuits at the west terminal, are, therefore, placed on the particular west-east speech channel which happened to be last preselected; no two consecutive speech fragments of vocal interval duration can be placed on the same speech channel in view of the preselection feature. The use of distinctive frequency tone signals transmitted with the speech for controlling the apparatus at the receiving end is a particularly valuable feature as it eliminates the necessity of providing apparatus operating in synchronism at each end of the line.

The arrangement functions in a similar manner for east-west transmission, the speech fragments of vocal interval duration being applied to speech channels 44, 45 and 46 as preselected by switching apparatus 53 and the accompanying control tones being applied to control channel 47.

It will be clear from the above description that it will be very difficult for unauthorized persons, who may attempt to listen in on the speech channels, to interpret the messages being transmitted thereover as there will occur, on any one of the speech channels, snatches of several different conversations, these conversation parts appearing in a purely random manner. The idea of pre-selecting the next idle channel at the time a speech fragment of vocal interval duration is applied to a channel is particularly valuable as it assures that two consecutive speech fragments of vocal interval duration will not be applied to the same channel.

The arrangement is also effective as a channel saver. Thus, in the system disclosed, only six one-way speech channels and two control channels are utilized for the interconnection of ten subscribers. With a larger number of subscribers it is possible to closely approach the condition of having only one-third as many speech channels in one direction as there are subscribers and yet provide adequate facilities for uninterrupted transmission. Thus, substantial operating economies are obtained by taking advantage of the previously recognized fact that during the time two subscribers are connected over a four-wire circuit, one side of the circuit is actually in use only about one-third of the time. This is to say, during sixty seconds of conversation time, one side of the line is in use twenty seconds, the other side is in use twenty seconds, and both sides are idle twenty seconds. Where many long and expensive circuits are involved this wasted time has long been recognized as undesirable; the present invention by utilizing fewer circuits largely eliminates it.

Referring now to Fig. 2, a detailed showing is set forth of a portion of the switching apparatus of one of the terminals, for example, the west terminal, the switching apparatus of which is represented in Fig. 1 by box 52. In order to avoid confusing duplication of similar apparatus, only the switching apparatus associated with one subscriber's telephone set and sufficient of the apparatus common thereto and to other telephone sets to completely illustrate the operation of the entire system is disclosed.

Subscriber's set 132, which corresponds, for example, to subscriber's set 12 of Fig. 1, is coupled to transmitting line 133 and receiving line 134 by transformer 135, network 136 serving to provide a proper balance in the well-known manner. Transmitting line 133 may be connected, through operation of certain relays which will be referred to in detail subsequently, to any one of three west-east speech channels 142, 143 and 144; these speech channels correspond to speech channels 26, 27 and 42 of Fig. 1. Receiving line 134 may be connected, through operation of certain relays which will be referred to in detail subsequently, to any one of three east-west speech channels 145, 146 and 147; these speech channels correspond to speech channels 44, 45 and 46 of Fig. 1.

The major portion of the switching apparatus may be separated into three groups, one group being associated with each of the west-east transmitting channels. For example, it will be apparent from the subsequent description that relays 152, 153, 154, 155, 156, 157, 172, 173 and 174, oscillator 175 and filter 176 are associated, so to speak, with speech channel 142, that relays 182, 183, 184, 185, 186, 187, 202, 203 and 204, oscillator 205 and filter 206 are associated with speech channel 143 and that relays 212, 213, 214, 215, 216, 217, 232, 233 and 234, oscillator 235 and filter 236 are associated with speech channel 144.

Speech energy emanating from subscriber's set 132 follows two parallel paths, one path over transmitting line 133, through delay network 242 and out over one of the three west-east speech channels 142, 143 or 144, depending upon which group of relays is operated, and the other path through amplifier-detector 243 to the various relay circuits.

In general, selection of the west-east speech channel is dependent upon the position of brush 245 of rotary selector switch 246; operation of this selector switch when a speech fragment of vocal interval duration is applied to a channel is effective to preselect the next speech channel in a manner evident from subsequent description. The switch may be of the type disclosed in O. F. Forsberg et al. Patent 1,472,465 and comprises two banks 247 and 252, two brushes 253 cooperating therewith and a stepping magnet 253. It will be understood that the two brushes are mechanically coupled so that energization of stepping magnet 253 causes rotation of both brushes 245 and 254. Switch 246 is common to all of the subscribers' telephone circuits of the west terminal.

For purposes of further illustration of the invention, the operation of the circuits of Fig. 2 will now be described in detail. In the condition illustrated, relays 153 and 154 are operated over an energizing circuit traced from battery 272, brush 245, third contact of selector bank 247, conductor 273, break contact of relay 217, break contact of relay 186, winding of relay 154 to ground 274 and winding of relay 153 to ground

275. Assuming now that subscriber A speaks, speech energy originating at subscriber's set 132 is transmitted through transformer 135 into transmitting line 133. As the energy is delayed somewhat in its passage through delay device 242, let us first see what operations result from passage of a part of the energy through amplifier-detector 243.

In view of the fact that relay 154 is operated, we have a completed path, for the energy emanating from the amplifier-detector, through conductors 276 and 277, which results in the completion of obvious energizing paths for relays 152, 155, 156, 157, 172, 173 and 174 all of which relays operate.

Operation of relay 174 connects, through its two make contacts, transmitting line 133 to west-east speech channel 142 so that the speech energy after traversing delay device 242 is sent out over speech channel 142; operation of relay 173 connects through its two make contacts, the output of oscillator 175 through filter 176 to west-east control channel 232 whereby control tone f_1 is applied to the control channel at the same time the speech energy is applied to the speech channel. Filter 176 is designed to pass only a small band of frequencies, including the tone frequency f_1 , and prevents the transmission of transients with the control tone.

Operation of relay 155 completes a locking path over which relays 153 and 154 are held operated, this path being traced from battery 283, make contact of relay 153, make contact of relay 155, winding of relay 154 to ground 274 and winding of relay 153 to ground 275.

Operation of relay 152 is effective to remove battery 284 from the make contact of relay 285. Relays 285, 286 and 287 are associated with the switching circuits of a second subscriber and correspond respectively to relays 153, 183 and 213 of the circuits associated with subscriber's set 132; relays 288, 289 and 290 are also associated with the circuits of the second subscriber and correspond respectively to relays 152, 182 and 212. In the instance of relays 285, 286 and 287, however, a connection to battery is not obtained directly through a contact of the respective relay but only from the break contact of the associated relay in the circuits of set 132 and, then, only if said associated relay be in unoperated position. This arrangement is provided so that even if two subscribers were to start talking at the same instant there would be no chance of the speech of both being placed on the same channel. For example, with the circuits in the condition just described there is no chance of a second subscriber breaking in on channel 142 with subscriber A as operation of relay 152 has removed battery from the make contact of relay 285 whereupon the holding circuit for relays in the other subscriber's circuit corresponding to relays 153 and 154 in the circuit of subscriber A cannot be established. In the instance of the switching circuits of the third subscriber, the battery supply path also includes the break contacts of relays 288, 289 and 290 of the second subscriber's circuit; in the instance of subsequent subscribers' circuits the path includes the break contact of a corresponding relay of the preceding circuit. Thus, for example, if the second subscriber (B) and the fourth subscriber (D) were to start talking simultaneously, subscriber A being idle, subscriber B would be put on the next idle channel and connection of subscriber D thereto at the same time would be prevented due

to the break in the battery supply path resulting from operation of relay 288.

Operation of relay 156 causes a break in the path connecting certain relays of the group associated with channel 143 to channel selector brush 245; operation of relay 157 causes a similar break in the path connecting certain relays of the group associated with channel 144 to the channel selector brush. This is done in order to prevent a possible operation of control relays 183 and 184 or 213 and 214 at this time should the selector switch be rotated.

Operation of relay 172 completes an energizing path for stepping magnet 253, this path being traced from battery 292, make contact of relay 173, conductor 293, third contact of switch bank 252, brush 254, winding of magnet 253 to ground 294. Brush 254 is therefore stepped around to the second contact of bank 252 where it comes to rest. Had this contact been "busy," i. e., had battery been connected thereto due to operation of relay 202 or a corresponding relay of another circuit, brush 254 would, of course, continue its rotation until it reached an "idle" contact of bank 252.

As brushes 254 and 245 are mechanically coupled, rotation of brush 254 to the second contact of bank 252 causes a corresponding rotation of brush 245 to the second contact of bank 247. This rotation of brush 245 is effective to preselect channel 143 so that the next speech fragment of vocal interval duration emanating from any of the subscribers' telephone circuits of the west terminal is placed thereon. This preselection is accomplished by setting up an energizing path for those relays associated with other subscribers' sets which correspond to relays 183 and 184 associated with subscriber's set 132. In the instance of relays 183 and 184, this energizing path is prepared but not completed as relay 156 is now in operated condition; the path when completed, i. e., when relay 156 is deenergized, is traced from battery 272, brush 245, second contact of bank 274, conductor 295, break contact of relay 216, break contact of relay 156, winding of relay 184 to ground 296 and winding of relay 183 to ground 297. With this condition, therefore, the next speech fragment of vocal interval duration occurring in any of the circuits is placed on channel 143; should subscriber A cease talking long enough for the relays associated with channel 142 to restore to normal before any of the other west subscribers start talking, relays 183 and 184 will operate over the path described above and should he then resume speaking, the resulting speech fragment will be placed on channel 143.

Although battery 272 is removed from conductor 273 as soon as brush 245 leaves the third contact of bank 247, relays 153 and 154 remain in operated position due to the locking circuit through the make contact relay of 155.

Returning now to consideration of conditions on channel 142, speech originating at subscriber's set 133 is being transmitted thereover and a control tone of frequency f_1 is being transmitted over control channel 282. Let us now consider the effect of these signals at the receiving end of the system. As the receiving apparatus of the east terminal has not been illustrated in Fig. 2, let us refer instead to the receiving arrangement of the west terminal and assume that speech is coming in over speech channel 145 and that a control tone of frequency f_1 is being received over control channel 312. As filter 313 is de-

signed to pass only a small frequency band including f_1 , the incoming control tone is passed to amplifier-detector 314 and, after rectification thereby, causes operation of relay 315.

Operation of relay 315 connects, through its make contacts, speech channel 145 to receiving line 134 so that the incoming speech is transmitted into the receiving side of the telephone circuit of subscriber's set 132. A part of this received speech energy passes through amplifier-detector 322 and, after rectification thereby, causes operation of relay 316 and disables the transmitting line 133.

Considering again the transmitting circuit of Fig. 2, as soon as subscriber A pauses in his speech an appreciable period and speech energy is no longer passing through amplifier-detector 243, the relays associated with speech channel 142, that is, relays 152, 153, 154, 155, 156, 157, 172, 173 and 174 restore to unoperated position. As soon as relay 156 drops back to unoperated position, relays 183 and 184 operate over an energizing path traced from battery 272, brush 245, second contact of bank 247, conductor 295, break contacts of relays 216 and 156, winding of relay 184 to ground 296 and winding of relay 183 to ground 297. As corresponding relays of other groups are, as pointed out above, also in operated position the next speech fragment of vocal interval duration occurring in any of the telephone circuits of the terminal will be placed on speech channel 143 and control tone of frequency f_2 or corresponding frequency if another subscriber talks will be sent out over control channel 282.

Speech channel 144 and control tone f_3 are preselected in a similar manner when brush 245 is rotated to the first contact of bank 247 thereby connecting battery 272 to conductor 326 and setting up energizing paths for relays 213 and 214.

It will be understood, of course, that the other subscribers' sets of the terminal are provided with switching arrangements similar to that illustrated by Fig. 2. It will be understood further that the number of channels (both speech and control) in the system described is merely by way of example; more channels or less may, of course, be provided depending upon the traffic demands.

While a certain specific embodiment of the invention has been selected for illustration and detailed description, the invention is not, of course, limited in its application to this embodiment. The embodiment described should be looked upon as illustrative of the invention and not as restrictive thereof.

What is claimed is:

1. In a speech transmission system including a plurality of transmitters, an equal number of receivers, a plurality of transmission channels between said transmitters and said receivers, and means for impressing speech current produced by said transmitters on said channels, the method of maintaining secrecy during the transmission of speech from said transmitters to said receivers which comprises impressing speech on said respective channels in the form of individual speech fragments each of a duration equal to a vocal interval and preselecting an idle channel for transmission of the next succeeding speech fragment each time a speech fragment of vocal interval duration is impressed on a channel.

2. In a speech transmission system including

1. a plurality of transmitters, an equal number of receivers, and a plurality of transmission channels between said transmitters and said receivers, the method of maintaining secrecy during the 5 transmission of speech from said transmitters to said receivers which comprises impressing each successive speech fragment of a duration equal to a vocal interval produced by said transmitters on a different one of said channels, and preselecting an idle channel for the transmission of the next succeeding speech fragment of vocal interval duration each time a speech fragment of such duration is applied to a channel.
- 10 3. In a speech transmission system, a plurality of transmitters, an equal number of receivers, a plurality of transmission channels between said transmitters and said receivers, means for applying a speech fragment of a duration equal to a vocal interval produced by one of said transmitters to a selected one of said channels, and means operating upon application of a speech fragment of vocal interval duration to one of said channels for preselecting an idle channel for application of the next succeeding speech 15 fragment of such duration.
- 15 4. In a speech transmission system, a plurality of transmitters, a plurality of receivers, a plurality of transmission channels between said transmitters and said receivers, the number of said channels being less than that of said transmitters and said receivers, means effective upon production of a speech fragment of a duration equal to a vocal interval by one of said transmitters for connecting the output thereof to a selected one of said channels, means for maintaining said connection during the duration of said speech fragment and means effective upon application of a speech fragment of vocal interval duration to one of said channels for preselecting an idle channel for application of the next succeeding speech fragment of such duration.
- 20 5. In a speech transmission system, a plurality of transmitters, a plurality of receivers, a plurality of transmission channels between said transmitters and said receivers, means effective upon production of a speech fragment of a duration equal to a vocal interval by one of said transmitters for connecting the output thereof to a selected one of said channels, means for maintaining said connection during the duration of said speech fragment, means for preventing the connection of the output of another transmitter to said selected channel during the duration of said speech fragment, and means effective upon application of a speech fragment of vocal interval duration to one of said channels for preselecting an idle channel for application of the next succeeding speech fragment of such duration.
- 25 6. In a speech transmission system including an east terminal and a west terminal, a plurality of subscribers' telephone circuits at each of said terminals, a plurality of transmission channels between said terminals, the number of said channels being less than that of said telephone circuits, a plurality of groups of relays associated with each of said telephone circuits, the number of said groups being equal to that of said channels, one group being associated with each channel, means effective upon occurrence of a speech fragment of a duration equal to a vocal interval in one of said telephone circuits for connecting the output thereof to a selected one of said channels, and means operating upon application of
- 30 said speech fragment to said channel for causing operation of certain relays in all of said groups of relays associated with a second of said channels which is then idle, operation of said relays being effective to preselect said second channel for application of the next succeeding speech fragment of vocal interval duration.
- 35 7. In a speech transmission system including a pair of separated terminals, a plurality of speech transmitting sets at each of said terminals, a plurality of transmission channels between said terminals, the number of said channels being less than that of said sets, switching means for so interchanging the connections between said speech transmitting sets and said transmission channels that each successive speech fragment of a duration equal to a vocal interval produced by any of said sets at one of said terminals is placed on a different one of said channels, said switching means operating each time a speech fragment of vocal interval duration is applied to a channel to preselect an idle channel for application of the next succeeding speech fragment of such duration produced by any of said sets at said terminal.
- 40 8. In a speech transmission system including an east terminal and a west terminal, a plurality of speech transmitting sets at said east terminal, a plurality of speech receiving sets at said west terminal, a plurality of speech transmission channels between said terminals, a plurality of sources of control current of different frequencies at said east terminal, a control tone transmission channel between said terminals, switching means at said east terminal for so changing the connections between said speech transmitting sets and said speech transmission channels that each successive speech fragment of a duration equal to a vocal interval produced by any of said transmitting sets is placed on a different channel, a plurality of frequency responsive switching devices at said west terminal each of which is responsive to the characteristic frequency of one of said sources of control current at the east terminal, each of said frequency responsive devices being associated with a respective one of said speech receiving sets and being effective when operated to connect said receiving set to a predetermined one of said speech transmission channels, said switching means at said east terminal being effective each time a speech fragment of vocal interval duration is connected to a speech transmission channel to preselect an idle speech transmission channel for application of the next succeeding speech fragment of such duration produced by one of said speech transmitting sets and to connect one of said control current sources to said control tone transmission channel.
- 45 9. In a speech transmission system, a plurality of transmitters, an equal number of receivers, a lesser number of speech transmission channels between said transmitters and said receivers, a signal transmission path, a plurality of distinctive frequency sources associated with each of said transmitters, the number of said sources associated with each transmitter being equal to the number of said channels, means for applying a speech fragment of a duration equal to a vocal interval produced by one of said transmitters to a selected one of said channels, means operating upon application of a speech fragment of vocal interval duration to one of said channels for preselecting an idle channel for application of the next succeeding speech fragment

- of such duration, and means effective during application of a speech fragment of vocal interval duration to a channel for applying the tone produced by a selected one of the sources associated with that transmitter producing said speech fragment to said signal transmission path, the selection of said source being dependent upon which speech channel is selected for application of said speech fragment.
10. In a speech transmission system including an east terminal and a west terminal, a plurality of transmitters at the east terminal, an equal number of receivers at the west terminal, each of said receivers being adapted for connection with one of said transmitters, a plurality of speech transmission channels between said terminals, the number of said channels being less than the number of transmitters and receivers, means at the east terminal for applying a speech fragment of a duration equal to a vocal interval produced by one of said transmitters to a selected one of said channels, means at the west terminal for connecting the receiver adapted to be connected to said speech fragment producing transmitter to said selected channel, and means at the east terminal operating upon application of a speech fragment of vocal interval duration to a channel for preselecting an idle channel for application of the next succeeding speech fragment of such duration produced by any of said transmitters.
11. In a speech transmission system including an east terminal and a west terminal, a plurality of transmitters at the east terminal, a plurality of receivers at the west terminal, each of said receivers being adapted to be connected with one of said transmitters, a plurality of speech channels between said terminals, the number of said speech channels being less than the number of said transmitters and receivers, a control tone channel between said terminals, a plurality of distinctive frequency tone sources associated with each of said transmitters, the number of said sources associated with each transmitter being the same as the number of said speech channels, means at the east terminal for applying a speech fragment of a duration equal to a vocal interval produced by one of said transmitters to a selected one of said speech channels and for applying a tone from one of the sources associated with the speech fragment producing transmitter to said control tone channel, means at the west terminal operating in accordance with the frequency of said applied tone for connecting the receiver adapted to be connected to said speech fragment producing transmitter to said selected speech channel, and means at the east terminal operating upon application of a speech fragment of vocal interval duration to a speech channel for preselecting an idle speech channel for transmission of the next succeeding speech fragment of such duration produced by any of said transmitters.
12. In a speech transmission system, a plurality of transmitters, a plurality of receivers, a plurality of transmission channels between said transmitters and said receivers, means effective upon production of a speech fragment of a duration equal to a vocal interval by one of said transmitters for connecting the output thereof to a selected one of said channels, means for preventing the connection of the output of a second transmitter to said channel while said first-mentioned transmitter output is connected thereto, and means effective upon application of a speech fragment of vocal interval duration to one of said channels for preselecting an idle channel for application of the next succeeding speech fragment of such duration.
13. In a speech transmission system including an east terminal and a west terminal, a plurality of transmitters at the east terminal, a plurality of receivers at the west terminal, a plurality of speech transmission channels between said terminals, a signal transmission channel between said terminals, means effective upon production of a speech fragment of a duration equal to a vocal interval by one of said transmitters for connecting the output thereof to a selected one of said speech channels, means for applying a distinctive signal tone to said signal channel effective to connect a selected one of said receivers to that speech channel to which said speech fragment producing transmitter is connected, and means for preselecting an idle speech channel, said two last-mentioned means also being effective upon production of said speech fragment by said one transmitter.
14. In a speech transmission system including an east terminal and a west terminal, a plurality of subscribers' telephone circuits at each of said terminals, a plurality of transmission channels between said terminals, a plurality of groups of relays associated with each of said telephone circuits, each of said groups being associated with one of said channels in the sense that connection of a channel to a telephone circuit is dependent upon operation of a relay in the respective group of relays associated with said channel, means effective upon occurrence of a speech fragment of a duration equal to a vocal interval in one of said telephone circuits for connecting a preselected one of said channels to said telephone circuit in which said speech fragment occurs, whereupon said speech fragment is applied to said preselected channel, means effective upon application of said speech fragment to said preselected channel for causing operation of certain relays in all of said groups of relays associated with a second channel which is then idle with the exception of the group associated with that telephone circuit in which said speech fragment occurs, and means for preventing the operation of the relays in said last-mentioned group which correspond to those relays in the other corresponding groups which are operated, said last-mentioned means being effective during duration of said speech fragment, operation of said relays in said groups associated with said second channel being effective to preselect said second channel for application of the next succeeding speech fragment of vocal interval duration.
